UNITED STATES PATENT OFFICE.

HARRIET LYONS REDMOND, OF BOSTON, MASSACHUSETTS, ASSIGNOR TO THE
WILLIAM CARTER COMPANY, OF NEEDHAM HEIGHTS, MASSACHUSETTS, A
CORPORATION OF MASSACHUSETTS.

UNDERGARMENT.

1,414,205.

Specification of Letters Patent. Patented Apr. 25, 1922.

Application filed February 2, 1921. Serial No. 441,905.

To all whom it may concern:

Be it known that I, HARRIET LYONS REDMOND, a citizen of the United States, and a resident of Boston, in the county of Suffolk 5 and State of Massachusetts, have invented an Improvement in Undergarments, of which the following description, in connection with the accompanying drawings, is a specification, like characters on the drawings representing like parts.

This invention relates to undergarments, and particularly to union undergarments intended for use by women.

In order that the principle of my invention may be readily understood, I have disclosed a single embodiment thereof in the accompanying drawings, wherein—

Fig. 1 is a front elevation of a garment embodying my invention, a portion of the structure being shown in dotted lines;

Fig. 2 is a vertical central section of the structure shown in Fig. 1;

Fig. 3 is an elevation of a detail of the invention;

Fig. 4 is a rear elevation of the garment shown in Fig. 1; and

Fig. 5 is an outside edge elevation with a part of the structure shown in dotted lines.

The undergarment of my invention may 30 be an undergarment for the upper part of the body only, but I have herein chosen to represent my invention as embodied in a union garment of knitted material. While I shall specifically describe the structure shown, I desire it clearly to be understood 35 that the invention is not limited to a union garment, nor to a knitted undergarment.

The undergarment is indicated generally at 1. It is preferably of knitted material, 40 and the wales thereof extend longitudinally of the garment throughout the main portion thereof, excepting as hereinafter described. This gives great transverse or lateral elasticity to the garment. Preferably I provide at 45 least one knitted insert in the garment in which the wales extend transversely of the garment, so as to provide great elasticity in the direction longitudinally of the garment. For that purpose and as shown most clearly 50 in Fig. 4, I insert a piece 2 of knitted material, wherein the wales extend transversely of the garment. Preferably the insert 2 extends from side to side of the garment and

at its ends is secured in position by an elastic seam formed by overseaming or otherwise as 55 indicated at 3. Preferably such seam continues to the upper edge of the garment, but if desired the entire upper part of the garment may be made in an integral tubular piece. The seam 3 may extend downward 60 as far as desired, and I have here indicated it as terminating at the point 4.

I have indicated a tape 5 extending transversely of the garment and suitably secured thereto across the back, said tape having provisions 6 preferably analogous to a glove fastener for attaching thereto a sanitary apron not herein disclosed and claimed in my co-pending application Serial No. 441,902.

Preferably and as stated the garment 1 is of knitted material, and the wales thereof, excepting in the insert 2, extend longitudinally of the garment. Interiorly of the garment I provide means for attaching a napkin 75 or the like and have herein for the purpose represented tapes 7 extending from the upper edge of the garment or from the binding member 8 at the front of the garment down to substantially the point 9, though this position may be varied, and at the rear of the garment down to the point 10 at the upper edge of the insert 2. Preferably the tapes 80 are of knitted material, and the wales thereof extend longitudinally of the tapes, 85 and hence in the general longitudinal direction of the wales of the body 1. The tapes 7 are as represented inclined toward each other sufficiently to meet or substantially to meet at their lower ends, but even with their 90 inclined construction the general direction of the wales thereof is substantially the same as the direction of the wales of the main or body portion of the garment.

At their lower ends the tapes may be secured together if desired, and they have attached thereto tabs 11, 12 at the front and rear, and preferably through the medium of elastic members 13, 14, a plurality thereof being shown at both front and rear. The 100 tabs 11, 12 may be employed for the reception of a safety pin or other fastening device, as is evident.

The union undergarment is of any suitable structure at the crotch portion, being 105 either an open crotch or closed crotch or

drop seat. The binding 8 at the top of the garment may be so constructed as to receive a tape, a portion of which is indicated at 15, and I preferably provide shoulder straps 16 of knitted material, but preferably more firmly knitted than the body 1, and if desired they may be warp knitted. Preferably the upper ends of the tapes 7 terminate just below the ends of the straps 16, so that the 10 line of pull of said tapes is transmitted to the straps 16.

While I have shown the garment as adapted to have attached thereto a sanitary apron, it is to be understood that this latter feature 15 may or may not be employed, and my invention is not limited in this respect.

The inserted piece 2, of a relatively great elasticity in a direction longitudinally of the garment, is desirably placed on a low 10 waist line giving the wearer the benefit of this elasticity when she bends.

The invention of this application is more particularly directed to the interiorly attached means for detachably receiving a 25 sanitary member. The undergarment having such feature may or may not be provided with an inserted elastic piece or pieces. My invention is not limited in this respect.

Having thus described one illustrative embodiment of my invention I desire it to be understood that although specific terms are employed, they are used in a generic and descriptive sense and not for purposes of limitation, the scope of the invention being 35 set forth in the following claims:

1. A knitted garment, the wales whereof in the main part of the garment extend longitudinally of the garment, the said garment having a knitted insert wherein the wales 40 extend transversely of the garment, and tapes secured to said main part of the garment and extending substantially from the upper edge of the garment to the meeting

edge of the main body of the garment and the insert thereof. 45

2. A knitted undergarment having the wales thereof extending longitudinally of the garment throughout the major portion thereof, said garment across the back having an insert wherein the wales extend transversely of the garment, and knitted tapes secured to the inner face of the garment at front and rear, the wales of said tapes extending substantially longitudinally of the garment, and the rear tapes extending substantially to the upper edge of the insert, 50 said tapes having at their lower ends tabs for the attachment of a sanitary member.

3. A union undersuit adapted to be worn next the flesh and having an opening at the rear, said garment being of knitted material and having the wales extending longitudinally but provided across the back with a knitted insert whereof the wales extend transversely, tapes secured to said garment 65 and extending from the upper edge of said garment downwardly at inclinations and meeting at front and rear, said tapes being of knitted material with the wales thereof extending longitudinally, and tabs for the 70 reception of a sanitary member elastically secured to said tapes.

4. A knitted garment, the wales whereof in the main part of the garment extend longitudinally of the garment, said garment having a knitted insert wherein the wales extend transversely of the garment, tapes secured to the main part of the garment and extending substantially from the upper edge of the garment to the meeting edge of the 75 main part of the garment and the insert thereof, and a tab secured to the lower ends of said tapes.

In testimony whereof, I have signed my name to this specification.

HARRIET LYONS REDMOND.
